[57] CLAIM

The ornamental design for a free standing fireplace, as shown and described.

DESCRIPTION

FIG. 1 is a top perspective view of a free standing fireplace showing our new design;

FIG. 2 is a front elevational view thereof;

FIG. 3 is a right side elevational view thereof, the left side being a mirror image of that shown;

FIG. 4 is a top plan view thereof;

FIG. 5 is a rear elevational view thereof;

FIG. 6 is a bottom plan view thereof; and,

FIG. 7 is an alternate embodiment thereof, with the glass doors shown removed, the only difference residing in the substitution of a griddle element for the top flue collar.
